UNITED STATES PATENT OFFICE.

WILLIAM J. OWENS, ALBERT L. GOODENOW, AND ALSON T. WHITING, OF UTICA, NEW YORK.

GRATE FOR FURNACES OR STOVES.

SPECIFICATION forming part of Letters Patent No. 247,995, dated October 4, 1881.

Application filed April 30, 1881. (No model.)

To all whom it may concern:

Be it known that we, WM. J. OWENS, ALBERT L. GOODENOW, and ALSON T. WHITING, citizens of the United States, residing at Utica, in the county of Oneida and State of New York, have invented certain new and useful Improvements in Grates for Hot-Air Furnaces, Stoves, and Steam-Heaters; and we do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

Our invention relates to improvements in grates; and it consists in details of construction that will be more fully set forth in the specification and claims, and pointed out in the drawings, in which—

Figure 1 is a plan view of the main grate. Fig. 2 is a vertical section of the same. Fig. 3 is a section of the main-grate support and the rocking mechanism for the supplemental-grate bars. Fig. 4 is a plan view of a supplemental-grate frame and supplemental-grate bars. Fig. 5 is a perspective view, partly in section, of the main-grate frame and its actuating mechanism. Fig. 6 is a plan view of the support to the main-grate frame. Fig. 7 is a detail view, showing the end of supplemental-grate bars journaled in the ends of the supplemental-grate frame. Fig. 8 is a perspective view of one of the supplemental-grate bars and the rocking mechanism. Fig. 9 is a perspective view of the mechanism for locking the grate-support to the furnace. Fig. 10 is a section showing the mechanism for locking the main grate to the supplemental-grate frame. Fig. 11 is a perspective view of our device.

Referring more particularly to the drawings, A is the main grate, of circular form, provided with the outwardly-projecting points a' and a groove, a'', which fits a roller, O. The grate-bars proper, D', project inwardly and downwardly, leaving at their inner edges a rectangular space, P.

D D are grate-bars extending inwardly and downwardly, and connecting with bars D'', which form a track on which a lower supple-

mental frame, B, rests and moves. The main-grate frame is placed on a circular grate-rest, G, which is provided with three slots or passages, N, which receive the rollers O. These openings N are made preferably wedge-shaped on the under side, Figs. 2 and 3, so as to provide more room for the free discharge of ashes, &c. This grate-rest G is further provided with slots W to engage with the lugs L on the frame A.

In order to lock the frames A and B together and compel frames A and B to move in unison, the lug L on frame A is moved out of slot W, and frame A is turned to the right, so as to cause the lug to slide underneath the grate-rest G. This is done when the two frames are first placed in position. The grate-rest G is provided with the slots W and sockets N in which rollers O move. These rollers support the main frame A, and the distance they can travel is limited by the length of the sockets N.

Attached to the main frame is a handle, K, which in reality is an extension of said frame, being cast in one piece with it. The movement of this bar or handle is limited by the sides of the furnace frame or support Y'. (Indicated in dotted lines in Fig. 11.)

The grate-rest G is provided with the trunnions x, which rest in the sides of said frame Y'. The support G has secured to and depending from it a plate, M, provided with rigid horizontal pins F, upon which rest the bearings E of the grate-bars C. These grate-bars are journaled in a supplemental frame, B, which slides out and in on a track formed by the extension D'' of the grate-bars D.

The outer journals of bars C are held in position by a cap, Q, let into the frame B, and secured to said frame by screws or in any other suitable way. The several parts of the grate are placed in position in the following manner: The trunnions x of grate-rest G are placed in their beds on the frame Y', and the front part of the rest is dropped down. The rollers O are then placed in the open socket N. The frame B is placed on the track D'' in the frame A, and this frame is then placed on the rest G, so that the lugs L come into the slots W. At the same time the groove in the under side of frame A rests on the rollers O.

The frame A is then moved to the right, so as to clear the lug L from the slot W. The rest G and the superincumbent parts are then raised up by means of the arm T, secured to rest G. Said arm passes between the projections of a lock-piece, p, and is secured by a pin, p', passing through slots p" in said lock-piece and an opening in the arm T. This lock-piece p is secured to the furnace-frame, and consequently the arm T is held securely in place.

When the parts are in position, as above explained, the lug L cannot get back to the slot W, for the reason that the rotary movement of the main frame (of which lug L forms a part) is limited in each direction by the play of the bar K, which has been before described. The grate-bars C being journaled in the frame B, when that frame is caused to move back and forth with frame A said bars will rock back and forth by virtue of the forked rests E moving on the pins F. In consequence of this construction and arrangement of parts when the two frames are caused to rotate the ashes and clinkers fall from the bars D D' on the bars C, and are thus broken up by the rocking motion of bar C, thus preventing choking and filling up of the space occupied by the frame B and bars C. When it is required to entirely remove the contents of the furnace the frame B may be drawn forward and the contents allowed to fall into the rectangular space P occupied by said frame. The frame is prevented from being drawn entirely out by reason of the stops of the frame coming in contact with the stops d on the track. By making this space rectangular we obtain for the same size of furnaces more room for the ashes, &c., than if the space was circular.

Ordinarily the clinkers are broken up by the rotary movement of the main-grate frame, but the clinkers, &c., which fall upon the center bars are not given any motion, and act to choke up the furnace and prevent free passage of air from beneath. In our device this is prevented by the motion given to the supplemental frame B and grate-bars C. Again, as the sockets N are made open, if any ashes or pieces of clinkers get into such sockets they will be broken up and will pass through to the ash-space.

Having thus described our invention, what we claim is—

1. In a furnace or stove, an upper main-grate frame provided with bars which extend downwardly and inwardly, substantially as described, so that the edges form a rectangular space, and having two horizontal bars attached to the corner bars of the main frame, to form a track upon which rests and slides a supplemental-grate frame, as set forth.

2. In a furnace or stove, a supplemental-grate

frame resting on a track formed by horizontal bars which are secured to the corner bars of the main-grate frame, and provided with rocking grate-bars journaled in said supplemental frame, the two frames being so joined together, substantially as described, that the movement of the main frame causes the supplemental frame to move in the same plane and give a rocking motion to the grate-bars, as set forth.

3. In a furnace or stove, the combination of an upper grate-frame, A, having locking-lugs, as described, a rest for said frame having slots 75 for the reception of the lugs, and a supplemental grate resting and moving on a track, which depends from and forms a part of the main grate, as set forth.

4. In a furnace or stove, an upper grate-frame provided with grate-bars D, which have extensions D", which extend downward and are connected together on opposite sides, thereby forming a track for a supplemental-grate frame, B, as set forth.

5. In a furnace or stove, a lower supplemental-grate frame, B, provided with grate-bars journaled in said frame, such bars having forked rests moving on pins, which are attached to a plate on the grate-rest, whereby a 90 rocking motion is given to said grate-bars when the supplemental-grate frame is rotated, substantially as described.

6. In a stove or furnace, the grate-rest G, having the open and wedge-shaped boxes N, 95 the slots W, and the locking-plate T, substantially as and for the purpose set forth.

7. In a furnace or stove, an upper or main grate frame provided with lugs L, adapted to engage with slots W in the grate-rest, so as 100 to lock said frame and rest together, substantially as set forth.

8. In a stove or furnace, a grate-rest, G, provided with a plate, T, secured to a lock, p, fastened to the under side of the furnace base 105 or frame, substantially as set forth.

9. In a furnace or stove, the supplemental frame B, sliding on a track, as described, and provided with revolving grate-bars, said bars being journaled in the frame and held in position therein by a removable cap, Q, substantially as set forth.

10. The combination, with a grate, of an operating-bar, K, provided with a socket or receptacle which has an orifice in its bottom, as 115 shown and described.

In testimony whereof we affix our signatures in presence of two witnesses.
